ABSTRACT

A device for threading the leading end of a web material from a roll or coil of such material to drive rollers or other advancing means of a motion picture projector, or the like, includes a hook member adapted to engage a perforation in the web and guide the web material away from the roll. A bifurcated guide arm is provided to cooperate with the hook member to accurately position the hook member for engaging the perforation in the web member.

WEB FEEDING APPARATUS WITH GUIDE ARM

CROSS REFERENCE TO RELATED
APPLICATIONS

Reference is made to commonly assigned copending United States Patent application Ser. No. 77,959 entitled, "MOTION PICTURE PROJECTOR APPARATUS" filed Oct. 5, 1970 in the name of William A. Martin et al; United States Patent application Ser. No. 113,922 entitled, "FILM FEEDING APPARATUS" filed Feb. 9, 1971 in the name of Edward S. McKee; and United States Patent application Ser. No. 250,940 entitled, "THREADING DEVICE" filed May 8, 1972 in the name of Clemens Hopfner et al.

BACKGROUND OF THE INVENTION

1. Field Of The Invention

This invention relates generally to threading devices for web materials and more particularly to a guide arm for accurately positioning a hooked member relative to a roll or coil of web material so as to accurately align the hook for engaging a perforation near the end of the web material.

2. Description Of The Prior Art

It is known to provide hook members to engage a perforation in a web material for engaging and extracting the web material from a roll or coil. For example, see U.S. Pat. No. 3,604,657 and the before-mentioned commonly assigned copending United States Patent Applications.

In the aforementioned copending Patent application Ser. No. 77,959, a film feeding mechanism is disclosed comprising a finger member having a hook on a free end portion thereof, the finger being movable to position the hook in close proximity to, or in engagement with, the outer convolution of any one of various sizes of film rolls that are rotatable about a spindle. As shown and described in that application, the film has a free end portion with an elongate opening therein, and the film is engaged by the hook entering that opening when the film is rotated in a take-up direction and the hook is extended to a position adjacent the film roll. After engagement of the film by the hook, the hook is moved to draw the leading end of the film away from the roll and furnish it to a threading mechanism of a motion picture projector or the like.

Copending Patent application Ser. No. 250,940 similarly discloses a threading device which is especially suitable for use with a roll of web material which may be contained within a cartridge. The threading device includes a pivotable member having secured thereto a hook portion that is adapted to be moved into close proximity with a roll of film contained in a cartridge. After the hook engages the opening in the leading end of a rotating roll, the hook extracts the leading end of the film from the cartridge and delivers it to transport apparatus of the projector wherein the hook is disengaged from the film and the hook is then returned to a retracted position.

Aforementioned copending Patent application Ser. No. 113,922 discloses an improvement suitable for use with the hook member in either of the mechanisms previously discussed. The improvement comprises guide members, such as wings or flanges, which are included on the member adjacent the hook for cooperating with flanges of a film reel and thereby accurately positioning

the hook with respect to the leading end of the film. The guide members are placed on the hook member to assure correct alignment and engagement between the hook and the opening in the web and, as a result, minimize the size of the opening required in the film so that the opening does not significantly impair operation with other types of film feeding mechanisms. While such guide members are satisfactory for applications where solid flanges are provided on the film reels, they are not as well suited for use where the flanges contain enlarged openings or where the flanges are not used. The present invention is suitable even in these applications to guide a hook member of the type previously disclosed for the guide mechanism of the present invention does not depend upon the flanges for assisting in accurately positioning the hook member with respect to the web.

SUMMARY OF THE INVENTION

An object of the invention is to provide an improved mechanism for threading a web material from a supply roll which can be either enclosed in a cartridge or unenclosed, and more specifically, to provide a threading mechanism which is highly reliable in operation and which functions reliably with web materials having relatively small openings through which a portion of the mechanism is to be engaged.

Another object of the invention is to provide a structurally simple guide arm for accurately guiding a hook member which is adapted to engage an opening near an end of a supply of film, wherein the opening in the film can be small enough to permit operation without significantly impairing reliability of operation of the rest of the feeding mechanism.

Another object of the invention is to provide a structurally simple mechanism that does not require cooperation with flanges of a reel for accurately locating a hooked member with respect to the end of a roll or coil of web material.

In accordance with the present invention, apparatus is provided for feeding a leading end portion of a strip of web material from a roll which is rotatable in a direction for winding the web material onto the roll. The apparatus includes a bifurcated guide arm which cooperates with a hook member to guide it during movement of the member from a position wherein the hook portion is spaced from the roll to a position wherein the hook portion is adjacent the roll of web material for entering the opening in the strip to couple the hook portion to the strip in response to rotation of the roll in a take-up direction.

The invention and its objects and advantages will become more apparent in the detailed description of preferred embodiment presented below.

BRIEF DESCRIPTION OF THE DRAWINGS

In the detailed description of the preferred embodiments of the invention presented below, reference is made to the accompanying drawings in which:

FIGS. 1, 3, 4 and 5 are fragmentary plan view, partially broken away, illustrating a preferred embodiment of a feeding apparatus of this invention in a variety of operating positions;

FIG. 2 is a fragmentary perspective view of a portion of the apparatus shown in FIG. 1;

FIG. 6 is a view similar to a portion of FIG. 2 showing a preferred embodiment of the guide member cooper-

ating with the withdrawal hook of the apparatus to guide the withdrawal hook into engagement with a web material having an opening therein; and

FIG. 7 is a view taken generally along line 7-7 of FIG. 6 showing the guide member cooperating with the withdrawal hook to guide the withdrawal hook between the flanges of a reel.

DESCRIPTION OF THE PREFERRED EMBODIMENT

Because photographic apparatus are well known, the present description will be directed in particular to elements forming part of, or cooperating more directly with, the present invention, apparatus not specifically shown or described herein being understood to be selectable from those known in the art.

In order to more clearly understand the present invention, certain structures will now be described which are of a similar nature to the structures disclosed in the beforementioned United States Patent application Ser. Nos. 77,959 and 250,940, reference being made to those applications for a more complete explanation of such apparatus and their modes of operation.

Referring now to the drawings, the apparatus of the present invention is operable to feed a strip of web material, such as film F, from a roll 10 of such film. The film roll may be wound on a conventional film supply reel 12 having spaced reel flanges 14 and 16 (FIG. 7) at opposite sides of roll 10, or the roll may be wound upon a core without flanges. Also, as shown in FIG. 1, the flanges of the reel may have openings 14a therein without affecting the operation of the apparatus. The reel (or core) has an opening 12a in a hub portion thereof for positioning the reel on a spindle 20 of a motion picture projector (for example). Reel 12 may be furnished to the projector in a cartridge 13, but it is not essential to the operation of the apparatus.

Spindle 20 extends from a recessed portion 22a of a mechanism plate 22. As is well known in the art, the spindle can be driven in a film take-up direction indicated by the arrow 21 in FIGS. 1, 3 and 4 through a suitable tendency or friction drive (not shown) and, if desired, it may be positively driven in the same direction at high speed to facilitate rewinding of film onto the reel. Also, as is well known, either the spindle or the threading apparatus may be movable to each of a plurality of positions so that the projector can receive reels of both large and small film capacities in corresponding sized film cartridges. Movement of the spindle for accommodation of various sizes of film rolls and cartridges is disclosed in U.S. Pat. No. 3,583,655 entitled, "CARTRIDGE LOADED PROJECTOR OR THE LIKE" issued June 8, 1971 in the name of Robert J. Roman while a mechanism for providing movement of the threading apparatus is disclosed in the aforementioned commonly-assigned United States patent application Ser. No. 250,940 filed May 8, 1972.

As shown in the drawings, when the film roll 10 is driven in the film take-up direction indicated by arrow 21, a free leading end 11 is caused to rotate in a generally circular path in a plane above plate 22a and an irregularly shaped finger member 30 which has a hook 32 secured to portion 30a of finger member 30 is guided into a position with respect to end 11 and an opening 11a in the end portion 11 (shown in FIG. 6) such that the hook 32 can enter the opening 11a to en-

gage and extract the film F for guiding it to threading apparatus.

In the preferred embodiment, a sector-shaped arm 24 is pivotally mounted under mechanism plate 22 by a pivot pin 26 or other suitable means. A support member 34 is affixed to arm 24 and extends through an arcuate opening 23 in plate 22 wherein it supports a plate 36 which has a pivot pin 38 secured thereto. Finger member 30 is pivotally mounted about pivot pin 38 such that hook 32 is mounted in the same plane in which end 11 of film roll 10 is caused to rotate. As viewed in FIGS. 1, 3 and 4, finger member 30 is urged in a counterclockwise direction about pivot pin 38 by a spring 40 which is affixed to plate 36 and an extension portion 30b of finger member 30. Spring 40 urges the hook portion 32 toward film roll 10 for bringing the hook portion into close proximity with the outer periphery of the film roll. This mounting of the finger member 30 allows it to remain in contact with the film roll after the hook 32 contacts the film roll, if the arm 24 continues to be driven toward the film roll. As will be explained in detail later, the hook is guided accurately into a position with respect to the film so that an elongate slot 11a in film end portion 11 is in register with hook 32 once during each revolution of a film roll for engaging the hook and the film.

A rotatable drive member 28 is mounted by any known manner for movement in an arcuate slot 27 in arm 24 so that it can be brought into driving engagement with either side edge 27a or 27b of the slot. Although in the preferred embodiment, drive member 28 is made of a resilient material having a high coefficient of friction so as to drive arm 24, it is also possible for member 28 to include teeth to engage with teeth positioned along side edges 27a, 27b. Also, instead of drive member 28 being movable relative to arm 24, the arm 24 could be made movable relative to drive 28 similar to the embodiment disclosed in the aforementioned commonly-assigned copending U.S. Pat. application Ser. No. 250,940. The movement of drive member 28 into engagement with surface 27a while the member is being driven constantly in a counterclockwise direction causes arm 24 to be driven about pivot pin 26 from a position wherein finger member 30 is retracted or withdrawn from the roll 10 (FIG. 1) toward an extended position, as shown in solid in FIG. 4 wherein the hook is moved in close proximity to, or in engagement with the outer convolution of any of several sizes of film rolls that may be positioned on spindle 20. Similarly, when member 28 is engaged with surface 27b (as shown in FIG. 5) the hook is driven from its extended to its retracted position. Drive member 28 may be driven by any suitable means such as that disclosed in the aforementioned commonly-assigned copending U.S. Pat. application Ser. Nos. 77,959 and 250,940.

In U.S. Pat. application Ser. No. 77,959, alignment between the hook portion of the finger and the opening in the film is achieved by moving the finger in a path which brought the hook portion between the flanges of the reel. While this has proved to be satisfactory in operation, it is very desirable to provide quite accurate positioning of the hook portion with respect to the film roll in order to attempt to maximize the reliability of the film feeding apparatus, minimize the size of film openings, 11a, and to make it suitable for use with film rolls that also may be used on apparatus having film feeding mechanisms of the type described in U.S. Pat.

No. 3,552,683. Also, manufacturing tolerances, wear and deviations in alignment, etc., in film reels, the spindle and finger can adversely affect reliability of a film feeding mechanism of the type disclosed in the earlier application Ser. No. 77,959.

Many of the problems previously encountered were overcome by the invention disclosed in commonly-assigned copending U.S. Pat. application Ser. No. 113,922 wherein the finger member was provided with wings or flanges that cooperate with reel flanges to guide the member relative to the reel flanges. However, current use of flanges having enlarged openings and cores without flanges indicate a need for means to accurately position the hook portion with respect to the film roll without being dependent upon the reel flanges. This is achieved by the preferred embodiment of the present invention in a manner which will now be described in greater detail.

Referring now in detail to FIG. 2, a rotatably mounted shaft 42 projects through an opening in mechanism plate 22. Shaft 42 is secured to a bushing 44 which is suitably mounted in a boss portion of the projector housing (not shown). Secured to shaft 42, above the mechanism plate 22, is a guide arm 46 which has a suitably-shaped bifurcated end portion which defines arm portions 46a and 46b for receiving the hook portion 32 of finger member 30 therebetween. As the separation between arm portions 46a and 46b is only slightly greater than the thickness of the finger member 30, the ends of arm portions 46a and 46b include tapered surfaces 46c and 46d, respectively, to permit the guiding finger member 30 to be more readily received between the arm portions 46a and 46b as shown in greater detail in FIG. 6. As is best shown in FIG. 7, arm portion 46b includes an extension 47 that has a tapered surface 47a which is suitably inclined for positioning arm 46 relative to reel flange 16 to thereby assure that arm portions 46a and 46b are readily aligned between reel flanges 14 and 16. The dimension between the outside surface of arm portions 46a and 46b is slightly less than the inside dimension between reel flanges 14 and 16 of a standard film reel such that the arm portions can be inserted between the flanges whenever a reel having flanges is mounted upon spindle 20. This is desirable since it permits the invention to work with film reels that are only partially filled with film (as shown in FIG. 4).

Referring once again to FIG. 2, an arm 48 is secured to shaft 42 immediately below mechanism plate 22. Arm 48 includes a rounded end portion 48a comprising a cam follower which follows the surface of a cam member 25 secured to arm 24. A spring 50 is secured to arm 48 and a portion (not shown) of the mechanism plate 22 to urge the surface of a cam follower 48a into resilient contact with cam member 25 such that movement of cam member 25 through arm 24 causes relative movement of cam follower 48a. In operation of the mechanism, drive member 28 is engaged with surface 27a of the arcuate slot 27 (FIGS. 1 and 3) and, as it is driven, it causes arm 24 to be pivoted in a counterclockwise direction about pivot 26 such that hook 32 is moved toward its extended (FIG. 4) position. As arm 24 is moved, cam member 25 is shifted relative to the rounded end 48a of arm 48. The relative contour of surface 48a and a member 25 is such that arm 48 remains substantially stationary during initial movement of member 25. However, after the left end 25a of mem-

ber 25 passes the rounded surface 48a as shown in the bottom position in FIG. 4, spring 50 moves arm 48 in a counterclockwise direction, simultaneously moving shaft 42 and arm 46 in the same direction. Continued movement of arm 24 in the counterclockwise direction to the upper position indicated in solid in FIG. 4 causes the bifurcated guide arm 46 also to be moved through a corresponding range of positions as shown in phantom in FIG. 3 and in solid in FIG. 4.

After the hook portion 32 has been guided into position by guide arm 46 and the film has been engaged as shown in FIG. 5, drive member 28 is shifted into contact with surface 27b of opening 27 and the continued counterclockwise rotation of drive member 28 then will drive arm 24 in a clockwise direction about pivot pin 26, thereby causing the hook portion 32 to be withdrawn from the roll 10.

As arm 24 moves in the clockwise direction, the left end 25a of the member 20 again comes into contact with cam follower 48a and thereby overcomes the force applied to arm 48 by spring 50 causing clockwise direction of arm 48, shaft 42 and arm 46. The continued movement of arm 24 in this direction results in arm 48 returning to its initial withdrawn (FIG. 1) position. The movement of the finger member 30 away from the film roll feeds the end portion 11 of film F to a film drive which includes a driven roller or puck 52 and a pressure roller or puck 54 that jointly define a nip therebetween into which the film is delivered by the finger member. The cooperation of roller 52 and roller 54, when they are driven in the directions indicated, is effective to strip the film from the finger and to deliver the film to other portions of a self threading mechanism of a projector, such as a guide channel 56 or the like.

The invention has been described in detail with particular reference to a preferred embodiment thereof, but it will be understood that variations and modifications can be effected within the spirit and scope of the invention.

We claim:

1. Apparatus for feeding a leading end portion of a strip of web material from a roll of such material, said roll being rotatable in a plane in a direction for taking up web material onto said roll, and said strip having an opening in its leading end portion, the apparatus comprising:
  - a. a member having shank portion and a hook portion, the hook portion being engageable with said strip through said opening for feeding said strip of web material from said roll;
  - b. means mounting said member for movement between (1) a first position wherein said hook portion is separated from said roll, and (2) a second position wherein said hook portion is located in said plane adjacent said roll of web material for entering and opening in said strip to couple said hook portion to said strip in response to rotation of said roll in a take-up direction;
  - c. means coupled to said member for moving said member between said first and second positions; and
  - d. guide means selectively engageable with said member for guiding movement of said hook portion transversely relative to said plane of said roll and the direction of movement of said member during movement of said member from its first position to

its second position so that said hook portion of said member is aligned with said opening in said web material when said member is in its second position, thereby to insure coupling of said hook portion of said member with said strip of web material during rotation of said roll in a take-up direction. 5

2. Apparatus as set forth in claim 1 wherein said 10 guide means includes an arm having a surface adapted to engage said member for guiding movement of said member.

3. Apparatus as set forth in claim 2 wherein said shank portion of said member is of a predetermined width, and wherein said arm includes bifurcated portion which defines first and second sections which are 15 spaced by a distance which exceeds said predetermined width of said shank portion, said shank portion being received between said first and second sections and cooperating therewith for guiding the movement of said hook portion of said member.

4. Apparatus as set forth in claim 3 wherein said first section includes an inclined surface at an outer end thereof for assisting in receiving said shank portion between said first and second sections. 20

5. Apparatus as set forth in claim 3 wherein said arm is movable between (1) a first position wherein said arm is spaced from said member, and (2) a second position wherein said arm is effective to receive said shank portion of said member between said first and second sections for guiding movement of said member. 25

6. Apparatus as set forth in claim 5 wherein said means coupled to said member is operatively coupled to said guide means for effective conjoint movement of said member and said arm between their respective first and second positions. 30

7. Apparatus as set forth in claim 5 wherein said apparatus is adapted for receiving said strip of web material wound upon a reel having at least one flange located adjacent to said film roll and wherein said first section includes an inclined surface for assuring that said arm is received between said sections as said arm moves toward said second position, said first section is positioned on the side of said flange which is nearest to said roll such that said first section is effective for guiding movement of said member relative to said flange and said roll. 35

8. Apparatus for feeding a leading end portion of a strip of web material from a roll of such material, the roll being rotatable in a direction for taking up web material onto the roll, and the web having an opening in its leading end portion, the apparatus comprising: 40

a. a member comprising a shank portion and a hook portion, said hook portion being adapted to enter said opening in said web strip for feeding strip material from said roll; 45

b. means mounting said member for movement between (1) a first position wherein said hook portion is separated from said roll, and (2) a second position wherein said hook portion is adjacent said roll of web material for entering said opening in said strip to couple said hook portion to said strip in response to rotation of said roll in a take-up direction; 50

c. means coupled to said member for moving said member between its first position and its second position; 55

d. a guide arm positionable for contacting said shank portion of said member to guide movement of said hook portion during movement of said member from its first to its second position so that said hook portion of said member is aligned with said opening in the web material when the member is in its second position, thereby to insure coupling of the hook portion of said member with the strip of web material during rotation of the roll in a take-up direction; 60

e. means mounting said guide arm for movement between (1) a first position wherein said guide arm is spaced from said member, and (2) a second position wherein said guide arm is effective to cooperate with said member for guiding movement of said member; and

f. means coupled to said guide arm and said member for effecting conjoint movement of said member and said guide arm between their respective first and second positions. 65

9. Apparatus as set forth in claim 8 wherein said shank portion of said member is of a predetermined width, and wherein said guide arm includes bifurcated portion which defines first and second sections which are spaced by a distance which exceeds said predetermined width of said shank portion such that said shank portion can be received between said first and second sections to cooperate therewith for guiding the movement of said member. 70

10. Apparatus as set forth in claim 9 wherein said first section includes an inclined surface at an outer end thereof for guiding said shank portion between said first and second sections. 75

11. Apparatus as set forth in claim 10 wherein said first section further includes an inclined surface for assuring that as said arm moved toward said second position, said first section is positioned on the side of said flange which is adjacent to said roll, such that said first section is effective for guiding movement of said member relative to said flange and said roll. 80

12. In combination with apparatus for receiving and rotatably supporting a roll of web material, engaging means adapted to thread a leading end portion of said web material along a path directed away from said received roll, said engaging means being movable between (1) a first position wherein said means is engageable with said leading end portion of said web material through an opening therein in response to rotation of said roll, and (2) a second position wherein said means is separated from said roll, and guide means comprising: 85

a guide arm supported by said apparatus, said guide arm having a bifurcated portion defining two sections having an opening therebetween, said guide arm being movable in response to said movement of said engaging means between (1) a first position wherein said bifurcated portion of said guide arm receives said engaging means in said opening and aligns said engaging means relative to said opening in said web material, and (2) a second position wherein said bifurcated portion of said guide arm is separated from said engaging means. 90

13. The combination as set forth in claim 12 wherein said guide arm is moved between said first and second positions by control means which cooperate with said engaging means, said control means comprising: 95

a pivot member pivotally supported by said apparatus
and coupled to said guide arm;
a follower member secured to said pivot member for
following a portion of said engaging means for
causing pivoting motion of said guide arm between 5

said first and second position as said guide means
is moved between its first and second positions, re-
spectively.
